UNITED STATES PATENT OFFICE.

DAVID J. MAHONEY, OF BAYONNE, NEW JERSEY.

MARINE TOILET.

Application filed June 8, 1927. Serial No. 197,340.

My invention relates to marine toilets.

An important object of the invention is to provide apparatus of the above mentioned character, embodying the minimum number 5 of moving parts, whereby the construction is extremely simple, cheap to manufacture, and not liable to disarrangement.

A further object of the invention is to provide a single valve device for controlling 10 the passage of flushing water, to the bowl, with simple means to control the action of the valve elements of the valve device.

Other objects and advantages of the invention will be apparent during the course 15 of the following description.

In the accompanying drawings, forming a part of this specification, and in which like numerals are employed to designate like parts throughout the same,

20 Figure 1 is a side elevation of apparatus embodying my invention,

Figure 2 is a plan view of the same,

Figure 3 is an end elevation of the apparatus, taken at a right angle to Figure 1,

25 Figure 4 is a vertical section taken through the pump, on line 4—4 of Figure 2,

Figure 5 is a vertical section through the flushing valve device and pump, parts in elevation, and parts broken away, taken on line 5—5 of Figure 2,

Figure 6 is a vertical section taken on line 6—6 of Figure 5, and,

Figure 7 is a horizontal section taken on line 7—7 of Figure 4.

35 In the drawings, wherein for the purpose of illustration, is shown a preferred embodiment of my invention, the numeral 10 designates a bowl, provided at its bottom with a

40 tubular outlet neck 11, connected with an outlet pipe 12. The bowl 10 may be formed of porcelain or the like, while the outlet pipe 12 is preferably formed of bronze or any other suitable non-corrosive material.

45 Arranged above the outlet pipe 12 is a vertically arranged cylinder 13 of a pump. This cylinder is preferably formed of bronze or any other suitable non-corrosive material. Connected with the lower end of the cylinder is a T-coupling 14, also preferably formed

50 of bronze and suitably connected with the outlet end of the pipe 12. A discharge pipe 15 is connected with the outlet end of the T-coupling and leads to any desired remote point.

55 Mounted upon the top of the cylinder 13 is a head or cap 16, preferably formed of

bronze, equipped with a stuffing box 17, receiving a reciprocatory plunger rod 18 extending into the cylinder 13. Rigidly connected with the free end of the plunger rod 60 18 is a plunger 19, of any well known or preferred construction, and equipped with suitable packing. The plunger rod 18 and the metallic parts of the plunger 19 are preferably formed of bronze. It is thus seen 65 that the cylinder 13 has communication, beneath the plunger 19, with the bottom of the bowl 10.

The numeral 20 designates a casing of a single flushing valve device. This casing 70 is provided with a depending tubular neck 21, for connection with a pipe, not shown, which leads to a source of water, such as to the ocean level. The casing 20 is preferably formed of bronze. This casing is provided upon one side with a horizontal tubular neck 22, externally threaded for engagement within a screw-threaded coupling 23, formed upon the side of the cylinder 13, adjacent to its upper end, whereby the casing 80 20 is in communication with the cylinder upon the upper side of the plunger 19.

The casing 20 is provided at its top with a screw-threaded tubular neck 24, for engagement with a coupling sleeve 25, having 85 an upper horizontal flange 26, to engage upon the top of the flange 27, formed upon an elbow 28, which is preferably formed of bronze. Suitable packings 29 are arranged between the engaging parts, as is obvious. 90 The elbow 29 is connected to a flushing pipe 30, leading into a tubular portion 31, which in turn leads into the upper portion of the bowl.

The valve device casing 20 is provided upon its opposite sides, Figure 6, with trunnions 32, upon which are pivotally mounted the lower ends of links 33, which converge upwardly and are apertured for receiving a pin 34, passing through the forward end 95 of a hand lever 35, which may be generally vertically arranged. This hand lever is provided with a rigid triangular structure or connection, including a generally vertical arm 36 and a generally horizontal arm 37,

100 which are preferably formed integral with each other and with the lever. The rear end of the horizontal arm 37 is apertured and is pivotally connected with the top of the plunger rod 18 by means of a pin 38 105

110 or the like. The lever 35 is preferably provided with an aperture 39. Should it be

preferred to have the lever generally horizontally arranged, the horizontal arm 37 is disconnected from the rod 18 and links 33, and the lever is inverted and its forward end again pivoted to the pin 34 while the pin 38 is passed through the aperture 39.

The outlet end of the T-coupling 14 is provided with a horizontal valve seat 40 having an opening 41 formed therein. The opening is adapted to be closed by an upwardly opening check leaf valve 42, preferably formed of leather or other flexible material, and carrying upon its top a weight 43, preferably formed of brass. The outlet pipe 12 is provided at its outlet end with a horizontal valve seat 44, having an opening 45, adapted to be covered by an upwardly opening leaf or flap valve 46, preferably formed of leather or the like, and provided upon its top with a weight 47, preferably formed of brass. As more clearly shown in Figures 5 and 6, the valve casing 20 is provided in its bottom above and adjacent to the tubular neck 21 with an opening 48, surrounded by a tapered or conical valve seat 49, adapted to receive thereon an upwardly opening rolling or ball valve element 50, preferably formed of brass, composition, or any other suitable non-corrosive material. In the upper portion of the casing 20 and adjacent to the lower end of the tubular neck 24 thereof is a web 51, having an opening 52 formed therein, and a tapered or conical valve seat 53 formed upon its top, for engagement with a rolling or check ball valve element 54. This check ball valve element may be formed of brass, composition, or any other suitable material. Arranged above the check ball valve element is a stop element 55, formed of bronze or the like, to limit the upward movement of the ball element 54, but not perceptibly interfering with the passage of water.

The numeral 56 designates a tubular bonnet net preferably formed of bronze and having a reduced screw-threaded portion 57, engaging within a screw-threaded tubular neck 58, formed upon the casing 20. A rotatable rod or shaft 59 extends through this bonnet 56 and is provided at its outer end with a handle or crank 60, to turn the same. A transverse pin 61 carried by the inner portion of the shaft 59 slidably engages the bonnet 56 and prevents the shaft 59 from moving outwardly in a longitudinal direction. The shaft 59 is provided at its inner end with a pair of diametrically arranged radially extending shifting fingers or lugs 62, preferably formed integral therewith. One of these lugs is adapted to engage the lower ball element 50 while the other lug will simultaneously engage the upper ball element 54, thus retaining the lower ball element seated and holding the upper ball element 65 from its seat.

The operation of the apparatus is as follows:

Upon the up stroke of the plunger 19, the contents of the bowl 10 are withdrawn through the pipe 12 and enters the lower portion of the cylinder 13 and coupling 14, beneath the plunger, the valve 42 closing upon the up stroke of the plunger and the valve 45 opening. Upon the down stroke of the plunger, the valve 45 closes and valve 42 opens and the contents are discharged through the pipe 15, as is obvious. Upon the up stroke of the plunger 19, as above explained, ball valve element 50 is seated, while ball valve element 54 is unseated and the water contained in the cylinder 13 above the plunger 19 is forced through the flushing valve device and pipe 30 to the upper portion of the bowl. Upon the down stroke of the plunger 19, ball valve element 54 is seated while ball valve element 50 is unseated and water is supplied to the cylinder 13 above the plunger 19 to fill the same.

It frequently occurs that the valves 42 and 44 may become wholly or partly inoperative and that it is desired to operate the plunger 19 without supplying additional flushing water to the bowl, as such supply might cause the bowl to overflow. To take care of this situation, the handle 60 is turned for about a fourth of a revolution and the fingers 62 will hold the lower ball valve element seated while the ball valve element 54 is held from its seat. The seating of the ball valve element 60 cuts off the further supply of the flushing water, and the retaining of the ball valve element 54 unseated breaks the vacuum which might otherwise occur in the cylinder 13, above the plunger, thus permitting of the free and easy reciprocation of the plunger.

Particular attention is called to the fact that I employ a single flushing valve device embodying the two ball valve elements. This greatly simplifies the construction of the apparatus. The ball valve elements being free to turn or roll upon their seats, tend to clean themselves and the seats, preventing corroding. The arrangement of the ball valve elements in close relation permits of the control of their operation by the single shaft 59.

It is to be understood that the form of my invention, herewith shown and described, is to be taken as a preferred example of the same, and that various changes in the shape, size and arrangement of parts may be resorted to without departing from the spirit of my invention or the scope of the subjoined claims.

Having thus described my invention, I claim:

1. In a marine toilet, a bowl, a cylinder, a conduit connecting the bowl and one end of the cylinder, a check valve controlling communication between the conduit and cyl-

- inder, a discharge conduit connected with the same end of the cylinder, a check valve arranged within the discharge conduit, a plunger to reciprocate within the cylinder, 5 means to move the plunger, a single flushing valve device embodying a valve casing leading into the opposite end of the cylinder, said valve casing having an inlet opening and a valve seat surrounding the inlet 10 opening and an outlet opening and a valve seat surrounding the outlet opening, check ball valve elements arranged to engage said valve seats, and a conduit connected with the valve casing to receive the water from 15 its outlet opening and connected with the upper portion of the bowl.
2. In a marine toilet, a bowl, a cylinder, a conduit connecting the bowl and one end of the cylinder, a check valve controlling communication between the conduit and cylinder, a discharge conduit connected with the same end of the cylinder, a check valve arranged within the discharge conduit, a plunger to reciprocate within the cylinder, 20 means to move the plunger, a single flushing valve device embodying a valve casing leading into the opposite end of the cylinder, said valve casing having an inlet opening and a valve seat surrounding the inlet 25 opening, and an outlet opening and a valve seat surrounding the outlet opening, said valve seats being arranged in relatively close relation, check ball valve elements mounted upon the valve seats, common means to alternately hold one check ball valve element seated and the other unseated, and a conduit connected with the valve casing to receive water from its outlet opening and connected with the upper portion of the bowl. 30
3. In a marine toilet, a bowl, a cylinder, a conduit connecting the bowl and one end of the cylinder, a check valve connected within the conduit, a discharge conduit connected with the same end of the cylinder, a check 35 valve connected within the discharge conduit, a plunger to reciprocate within the cylinder, means to move the plunger, a single flushing valve device embodying a valve casing leading into the opposite end of the cylinder, said valve casing having an inlet opening and a valve seat surrounding the same 40 and an outlet opening and a valve seat surrounding the same, said valve seats being arranged in relatively close relation, check ball valve elements mounted upon the valve seats, a shaft extending into the valve casing between the valve seats, shifting elements carried by the shafts and adapted to engage the valve elements to alternately seat and open them, means to turn the shaft, and a conduit connected with the valve casing to receive water from its outlet opening and connected with the upper portion of the bowl. 45
4. In a marine toilet, a bowl, a cylinder having one end in communication with the lower portion of the bowl and also having a discharge outlet, valve means for controlling the inlet and outlet of water to and from the opposite end of the cylinder, a conduit connected with the outlet of valve means and in communication with the upper portion of the bowl, a plunger to reciprocate within the cylinder, a plunger rod connected with the plunger, a lever having a triangular portion provided at its ends with openings, a support having a pivot element for insertion within the opening at the forward end of the triangular portion, and a pivot element adapted to connect the plunger rod with either end of the rear portion of a triangular portion whereby the lever may be generally vertically or horizontally arranged. 50
5. In a marine toilet, a bowl, a cylinder, a conduit connecting the bowl and one end of the cylinder, a check valve controlling communication between the conduit and cylinder, a discharge conduit connected with the same end of the cylinder, a check valve controlling the discharge conduit, a plunger to reciprocate within the cylinder, means to move the plunger, a single flush valve device embodying a valve casing leading into the opposite end of the cylinder, said valve casing having automatic check valve controlled inlet and outlet openings, and a conduit connected with the valve casing to receive the water from the outlet opening and connected with the bowl. 55

In testimony whereof I affix my signature.
DAVID J. MAHONEY.
